UNITED STATES PATENT OFFICE.

JOHN J. BUCHANAN, OF WATERBURY, CONNECTICUT, ASSIGNOR TO WATERBURY BUCKLE COMPANY, OF WATERBURY, CONNECTICUT, A CORPORATION OF CONNECTICUT.

BUCKLE.

No. 896,359.

Specification of Letters Patent. Patented Aug. 18, 1908.

Application filed April 23, 1907. Serial No. 369,716.

To all whom it may concern:

Be it known that I, JOHN J. BUCHANAN, a citizen of the United States, and resident of Waterbury, in the county of New Haven and State of Connecticut, have invented certain new and useful Improvements in Buckles, of which the following is a specification.

This invention has relation to buckles, and it consists in the novel construction and arrangement of the parts as hereinafter shown and described.

The object of the invention is to provide a bag buckle the construction of which is such, as to insure a marked change of direction in the web when buckle is closed thereon, and to provide a tongue in said buckle having special means whereby it can be readily operated.

Said buckle consists of a frame and a tongue both parts of which are struck up from sheet metal in a way to form a neat, attractive, durable and easily operated buckle, especially adapted for bag straps, as will later be described in detail, and is illustrated upon the accompanying drawing forming a part of this specification, upon which similar characters of reference denote like or corresponding parts throughout the several figures and of which,

Figure 1 is a top plan view of the buckle. Fig. 2 is an edge elevation of the same showing (in dotted lines) a strap or web attached thereto and engaged thereby, and Fig. 3 is a perspective view of the buckle.

The buckle consists of the frame 1 and the tongue 2; both of which are struck and formed up from sheet metal. The tongue 2 is provided with a forward serrated edge 3, and at its middle with a lug 4 which is cut from the center of the body portion of the tongue and bent slightly up out of the plane thereof. The rear edge of the tongue is curled, as at 5. The frame 1 consists of the side bars 6, 6, and the cross bars 7, 8, 9 and 10. The intermediate cross bars 8 and 9 lie in the same plane and in the same plane as the intermediate portions of the side bars 6, while the forward cross-bar 7 is vertically disposed with relation to the intermediate portion of the side bar 6 and the lower edge 11 of the cross-bar 7 is in the same plane, or substantially the same plane, as the lower surfaces of the intermediate portions of the side bars 6. In forming the frame 1 up and in vertically disposing the cross-bar 7 as described, the lower

edge of the said cross-bar 7 may readily be brought into the same plane with the lower surfaces of the intermediate portions of the side bars 6 by reason of the fact that the said cross-bar 7 is provided at its end portion 60 with the recesses or incisions 12. The side bars 6 are provided upon their inner edges with the inwardly and oppositely disposed lugs 13, 13, which lie within the path of the tongue 2 and are adapted to limit the movement of the same. The curled end 5 of the tongue 2 is carried around the cross-bar 8 which serves as a pivot for the said tongue.

Immediately behind the cross-bar 9 the side bars 6 are vertically disposed, while the cross-bar 10 lies in a plane above and parallel with the plane in which the bars 6, 8 and 9 lie. The end of the web 14 (indicated by dotted lines in Fig. 2) is attached to the cross-bar 9 and passes through the loop formed by the said cross bars and the rear ends of the side bars 6 and the cross-bar 10. The free end of the said strap or web is passed between the broad face of cross-bar 7 and the serrated engaging edge 3 of the tongue 2, and the extremity of the said strap or web is slipped under the cross-bar 10. The tongue 2 at its serrated edge terminates short of the broad face of the cross-bar 7, to snugly engage the web or strap 14 which is contorted out of 85 alinement between the tongue 2 and the cross bar 7, which forms a means for positively engaging and retaining the said strap or web at the point of engagement.

What is claimed is:—

A buckle comprising a rectangular frame, a cross-bar between the side bars of said frame, a pivot bar between said side bars and on the same plane with said cross-bar and said frame, a flat tongue on said pivot bar having 95 its under face on a plane with the upper face of said frame, an end bar contiguous with the free end of said tongue and presenting a practically vertical wall in opposition thereto, an end bar at the other end of said frame, and 100 means for controlling the movement of said tongue.

Signed at Waterbury, in the county of New Haven, and State of Connecticut, this 16th day of April, A. D. 1907.

JOHN J. BUCHANAN.
